UNITED STATES PATENT OFFICE.

WILLIAM W. LE GRANDE, OF LOUISVILLE, KENTUCKY, ASSIGNOR TO THE NATIONAL ELECTRIC RAILWAY SIGNAL COMPANY, OF SAME PLACE.

ELECTRIC RAILWAY-SIGNAL.

SPECIFICATION forming part of Letters Patent No. 287,446, dated October 30, 1883.

Application filed April 6, 1883. (No model.)

To all whom it may concern:

Be it known that I, WILLIAM W. LE GRANDE, a citizen of the United States of America, residing at Louisville, in the county of Jefferson and State of Kentucky, have invented certain new and useful Improvements in Electric Railway-Signals; and I do hereby declare the following to be a full, clear, and exact description of the invention, such as will enable others skilled in the art to which it appertains to make and use the same.

This invention relates to that class of visual railway-signals in which a semaphore or disk has its position changed by the influence of electro-magnetism.

The object of the invention is to secure an efficient and prolonged action of an armature under the attractive influence of a magnet in opposition to normal force, so that a visual signal held normally in one position by gravity may be given an extended movement, causing a readily-observable change of its location.

My invention is applicable to night as well as day signals; and it consists in a novel construction and combination of devices, which will be readily understood from the following particular description in connection with the accompanying drawings, in which—

Figure 1 is a front view of a railway-signal constructed according to my invention. Fig. 2 is a rear view thereof, with the door of the casing open. Fig. 3 is a vertical section on the line $x-x$ of Fig. 1. Fig. 4 is a detached perspective view of the signal-disk, magnet, and armature, and Fig. 5 is a detached view, in elevation, of the magnet and armature.

Referring to Fig. 1, the letter A indicates a circular signal-ease, having in its front wall a series of openings, a , through which may be observed a signal-disk, B, which is mounted within the casing on a central shaft, b , the front end of which has its bearing at the center of the front wall of the casing, while its rear end is supported by a standard, c , within the casing. This shaft b is provided with radial arms d , which support a segmental soft-iron plate, E, which is slightly eccentric to the shaft, and serves as the armature of an electro-magnet, F, which is arranged below it on a suitable block of wood or other base-piece

at the bottom of the casing. The signal-disk is provided near one edge with a counter-weight, W, mounted on a suitable pin, and which holds the disk normally in a given position with respect to the openings in the front wall of the casing. The movement of the disk by gravity is limited by a stop-pin, p , projecting inwardly in the path of the pin which carries the counter-weight, and its movement in the opposite direction is limited by a similar pin, p' . The distance which these pins allow the disk to move is such that when said disk performs a complete movement, the portion which is visible at any time through the openings in the casing will be entirely removed from said openings and concealed behind the wall, while fresh portions of the disk will be brought into view. The disk may be painted or otherwise colored in spots or sections, so arranged that when the disk is in its normal position one color will show through the openings in the casing, and when it is moved its full distance another color will show. The disk moves edgewise, and therefore meets with hardly any resistance from the air.

The armature F is so supported upon the shaft b that when the signal-disk is held in its normal position by gravity, the said armature will be held away from the position in front of the poles of the magnet, but with one edge adjacent to said poles and within attractive distance thereof, while the other edge is considerably elevated. Now, owing to the eccentricity of the segmental armature, if the magnet be charged, said armature will be moved in a path across the ends of the magnet-cores, and as it moves in response to the attraction of the magnet, the distance between its surface and the poles of the magnet will be gradually decreased in that portion which is approaching the magnet, and increased at that portion which is receding from the magnet, so that the movement of the armature in the desired direction will not be retarded by counter-attraction. Supposing the parts to be in position, as shown in full lines, Fig. 2, if the magnet should now be charged, the armature will be attracted to the position indicated by dotted lines, thus giving the signal-disk a partial rotation in opposition to the gravity of

the weight W, until the pin supporting the weight strikes the upper stop, p', this movement of the disk causing a different color to be shown through the openings in the casing 5 from that which is exposed when the disk is held in its normal position by gravity. When the circuit of the magnet is broken and its cores lose their attractive power over the armature, the counter-weight will cause the disk 10 to return to its original position.

I do not limit myself to any particular form of movable signal, as it is obvious that a properly-weighted semaphore-arm may have its position changed by the alternate action of 15 gravity and a properly-attached armature arranged in the relation shown to an electromagnet.

The signal shown in the drawings is adapted for either day or night use, as the disk may 20 be composed of a material through which the light of a lamp will be properly transmitted to illuminate those portions of the disk which show through the openings in the casing. The letter Q designates a lamp supported upon 25 suitable shelf behind the signal-disk within the casing.

I have designed my improved signal especially for use in connection with the improved

railway-signal circuit described in Patent No. 272,276, granted to me on the 13th day of February, 1883; but it may obviously be used in other circuits, either closed or open.

Having now fully described my invention and explained the operation thereof, I claim—

1. The combination, with the casing having 35 openings in its front wall, of the signal-disk mounted on a shaft within said casing, and held in a normal position by gravity, the electro-magnet, and the segmental eccentric-armature secured to the shaft of the signal-disk, 40 substantially as described.

2. The combination, with the casing having 45 openings in its front wall, of the signal-disk formed of light-transmitting material, the electro-magnet, the eccentric segmental armature, the lamp for illuminating the signal, and a counter-weight for returning the signal, and suitable means for connecting the magnet to a battery, essentially as set forth.

In testimony whereof I affix my signature 50 in presence of two witnesses.

WILLIAM W. LE GRANDE.
